FOLDING MACHINE

Leo M. Kahn, New York, N. Y., assignor to The American Laundry Machinery Company, Norwood, Ohio, a corporation of Ohio

Original application September 22, 1939, Serial No. 296,059. Divided and this application November 27, 1940, Serial No. 367,410

12 Claims.

(CL. 270—61)

This invention relates to improvements in machines for folding articles, particularly flat fabric articles of sheet or web form.

The invention resides in the structure shown in the accompanying drawing and adapted to perform the functions described in the attached specification. The novel features will be summarized in the claims.

The drawing is a perspective view of a machine embodying my invention.

The device shown comprises a supporting frame of four uprights 300 which carry a table 302 which is a section of a right circular cylinder. They also carry a shaft 304 positioned along the axis of the table. A pair of arms 306, fixed to shaft 304, extend beyond the table and carry between their outer ends a rod 308 having a spring clasp 310 thereon. A pivoted pedal 312 at either end of the machine may be moved by the person running the machine. It is connected by linkage 314 both to the clasp 310 and arms 306. The linkage is such that a motion of the pedal first shuts the clasp and then moves the arms 306 away from their normal central position.

There is at least one slot 316 in the table and perpendicular to shaft 304. A bar 318 lies under the table and parallel with its axis and is carried by arms 320 which are rotatable about shaft 304 and connected by linkage 322 to arms 306 in such fashion that they move in one direction from an upright position at the same speed that arms 306 move in the other direction. When arms 306 and 320 are upright, the machine is in neutral and a general switch 324 may be held open by any convenient part such as linkage 322.

An article to be folded is attached at its forward end to clasp 310 and the rod 308 is pushed away from the operator. That motion may be brought about (1) by moving pedal 312 or (2) automatically upon the closing of the clasp or (3) by hand. Simultaneously, bar 318 moves backward until it meets the rear end of the article. When the article is first laid over the slot 316 and the first motion of arms 306 permits closing of the main switch 324, a light 326 in bar 318 shines through slot 316, is reflected from the under surface of the article, and enters photoelectric cell 328 to get in readiness a clock-operated switch mechanism 330. When the trailing edge of the article passes off the cell 328, the latter ceases to function and thereby causes mechanism 330 to begin to act. At this moment, since arms 306 and 320 move with the same speed, the mid-point of the article is at the starting point of those arms. Mechanism 330 starts mo-

tor 332 which, through linkage 335, 334, pushes connecting rods 336 and so rotates arms 338 about shaft 304. A bent rod 340 is rotatably held in the outer ends of arms 338 and normally held as far as possible above table 302 by spring 342. When arms 338 have reached vertical position (or slightly beyond—to take into account the time of action of these arms), cams 344 rotate rod 340 down so as to tightly press the mid-point of the article against the table.

At about the same time, but determined by mechanism 330, solenoid 346 begins to pull linkage 348 whereby levers 349 are pulled, drawing with them arms 350 by means of links 351 so as to rotate about shaft 304. The arms 350 carry at their ends a stiff apron 352 above table 302. Arms 350 normally are at the far end of the machine and the apron extends back toward the top or center of the machine and from side to side. The apron pushes between clasp 310 and rod 340, pulling the front end of the article from the former and folding it back over the rod 340.

The extent of the motion of the apron is governed by extent of the motion of linkage 348 and that in turn is controlled by the solenoid-operated rod 347. The latter's motion is limited by a cam 349a on shaft 304. The farther rod 308 must be pushed before the mid-point of the article is at the mid-point of the table, i. e., at the starting point of arms 306, the more of the article there is to be folded back and the farther the apron 352 must push. Cam 349a turns with arms 306 and is so shaped that the farther they go the farther rod 347 may go and so the farther apron 352 may go.

The article has now been folded in two. Lever 312 may be released. Arms 306 come back to neutral, shutting off the main switch and the other parts return to their neutral positions. The folding apron is equivalent in result to a folding blade for pushing the article double between two rolls.

The machine shown may also be adjusted so as to fold an article into three layers. Linkage 322 is connected to each of the arms 320 at a point 354 half as near to shaft 304 as in the case of a single fold. This results in bar 318 moving twice as fast in one direction as does rod 308 in the other. Hence, the latter comes out from under the rear edge of the article when that rear edge is twice as far from the table mid-point as is the leading edge. Therefore, rod 340 overlays the article at one-third its length and apron 352, by moving over it, causes the first fold there.

Next, the linkage 334 is caused, by the con-

necting rod 335 connecting it to motor 332, to reverse direction and draw rod 340 out of the first fold. After it has returned to its starting point, it is carried forward again, first under the rear end of the article and then over the apron so as to fold the last third of the article over the edge of the apron which has stopped (by cam 349a) as far beyond the table mid-point as the rod 308 went on the other side. The pedal may then be released and the entire machine comes 10 to rest.

It will be seen that rod 340 makes two complete sweeps back and forth for one sweep back and forth of the apron 352. While the rod 340 is forward the first time, it overlies the article so that the apron can make the first fold. Then the rod returns to its starting position at the end of the machine. The second sweep forward begins with the rod close to the table so as to be under and to pick up the rear end of the article and continues with the rod elevated slightly more above the table so as to pass over to fold the article over the apron which has not returned to its starting position. The starting positions of rod 340 and the apron are shown in the drawing. Rod 308 and bar 318 are there shown as just having left their starting positions.

The mechanism next described is the second stroke which causes the rod 340 to be pressed upon the table only during the starting portion of its second sweep forward. Its forward and backward motion is caused by connecting rod 335. Gearing 355 run by motor 332, gives cam 356 one revolution while the end of connecting rod 335 is carried twice about a circle. Pivoted cam 358 has one end in contact with cam 356 and the other end lying along the edge of the table at the starting point of the path of the end of pivotable rod 340. With every second swing forward of the rod 340, cam 358 swings into 40 the path of the end of the rod and depresses the rod, whereby the latter is brought into contact with the surface of the table so as to get under the trailing edge of the article to be folded over the apron 352. Normally rod 340 is held above the table surface by the spring 342.

A spring 360 is positioned from the frame of the machine to the lever 350 to return the same to its starting point after the operation is complete. At this final stage, a lever 361 may now 50 make a third fold by rotating 180 degrees and pressing the already folded article between the folding rollers 362 onto the carry-off conveyor 363 to the stacking machine.

This application is a division of my copending application Serial No. 296,059, filed September 22, 1939.

What I claim is:

1. A folding machine comprising means for fixing a portion of an article in position, and means for operating said fixing means when the mid point of one side of the article is adjacent said fixing means, and means for folding the article about the portion thereof which is fixed in position.

2. A folding machine comprising means for fixing a portion of an article in position, means for operating said fixing means when the mid point of one side of the article is adjacent said fixing means, means for folding the article about the portion thereof which is fixed in position, and other means for folding the article again along an edge of the first-mentioned folding means, said means operating independently of the size of the article.

3. A folding machine comprising hand-controlled means for moving an article forward, means for fixing a line of fold in the article, the last mentioned means being operated by the first-mentioned means, and means for folding the article about said line of fold.

4. In a folding machine, a table, means for releasably holding the forward end of an article, said means being movable in a forward direction from a starting point, article measuring means movable in timed relation to said first named means in a rearward direction from said starting point, means controlled by said measuring means for clamping a portion of said article to said table, and means for folding part of said article over said clamping means.

5. In a folding machine, the combination of claim 4 wherein said table is arcuate about an axis, and each of said means is controlled by an arm oscillatable about said axis.

6. In a folding machine, the combination of claim 4 including operator-operated means for securing the forward end of an article to said first named means and for concurrently moving said first and second named means in opposite directions.

7. In a folding machine, a table for supporting an article to be folded, two measuring elements movable in opposite directions from a starting line on said table, means for folding said article adjacent said starting line, and actuating means for said folding means responsive to movement of one of said elements to the end of said article.

8. In a folding machine, a table, means for releasably holding the forward end of an article, said means being movable in a forward direction from a starting point, a folding blade movable rearwardly to fold said article approximately at said starting point, and means coordinating the movement of said blade with the movement of said first named means.

9. In a folding machine, a table, an arm adapted to releasably hold the forward end of an article, said arm being movable in a forward direction from a starting point, a second arm movable in a rearward direction in timed relation to said first named arm, clamping means adapted to clamp said article at said starting point, means for actuating said clamping means when said second arm reaches the rear end of an article, and a folding blade movable rearwardly and adapted to fold the forward end of the article rearwardly over said clamping means.

10. In a folding machine, a table for supporting an article to be folded, an arm adapted to releasably hold the forward end of an article lying on said table, said arm being movable in a forward direction from a starting point, means for fixing a line of fold approximately at said starting point when the forward end of said article has moved a predetermined distance, a first folding means for holding the forward end of said article rearwardly about said line of fold, and a second folding means for folding the rearward end of said article forwardly about said first folding means.

11. In a folding machine, a table for supporting an article to be folded, an arm adapted to releasably hold the forward end of an article lying on said table, said arm being movable in a forward direction from a starting point, a clamping arm for holding a portion of said article on the table approximately at said starting point when the forward end of said article has moved a predetermined distance, folding means for fold-

ing the forward end of said article rearwardly about said clamping arm, and means for moving said clamping arm rearwardly and beneath said article and for then moving said arm forwardly to fold the rearward end of said article forwardly.

12. In a folding machine, a table for supporting an article to be folded, an arm adapted to releasably hold the forward end of an article

lying on said table, said arm being movable in a forward direction from a starting point, means for fixing a line of fold for said article lying on said table, means for folding said article about said line of fold, and means moving through said table for cross-folding said article at right angles to said line of fold.
